TYPEWRITER WORD COUNTER

Filed April 30, 1927

UNITED STATES PATENT OFFICE

JESSE A. B. SMITH, OF STAMFORD, CONNECTICUT, ASSIGNOR TO UNDERWOOD ELLIOTT FISHER COMPANY, OF NEW YORK, N. Y., A CORPORATION OF DELAWARE

TYPEWRITER WORD COUNTER

Application filed April 30, 1927. Serial No. 187,790.

This invention relates generally to word-counters for typewriting machines, as, for example, counters for the words of telegraph messages.

Word-counters have been proposed in which two universal counting bars are displaceably mounted under typewriter key-levers to be depressed thereby. The depression of one of said counting bars, upon typing 5 the first letter of a word, is arranged to set up an actuating or potentially operative condition in register-operating mechanism, and the subsequent depression of the other counting bar, upon operation of the space-bar or 10 other desired elements of the keyboard, is effective to release said mechanism from said condition and restore it to normal starting position, the arrangement being for said mechanism to advance the units wheel of the 15 register one figure or step concomitantly with the depression of one or the other of said counting bars. It has been found that, as heretofore constructed, such word-counters can be misoperated by holding down the 20 space-bar and striking one of the letter-keys, each depression of which will be counted as a word as long as the space-key is held down. An object of this invention is to overcome 25 this weakness.

According to my invention, a register is operatively connected with an actuating mechanism including a pawl, an actuator or lever carrying said pawl, a latch and two universal counting bars displaceably mounted 30 under the key-levers of a typewriting machine to which the word-counter is attached. One of the counting bars is depressed upon typing the first letter of a word, and swings the actuator operatively connected to the 35 counting bars against spring-tension, so as to move the pawl backwardly, i. e., counter-clockwise far enough to let it engage behind a tooth in a usual ratchet-wheel of the register one full step or tooth to the rear of the 40 normal starting position of the pawl. The latch automatically latches the counting bar and actuator in this position, so that typing of other letters in the word do not affect the actuator. Subsequent operation of the space-bar or any other desired element of the key- 45

board may be arranged to depress the other universal counting bar, which is effective to move a rocking arm to release said latch, and at the same time control said actuator to prevent the return of the latter until the 55 space-bar and the counting bar controlled by it are allowed to rise, whereupon the actuator and drive pawl swing back to normal position, and the pawl moves the ratchet-wheel ahead one step. A link operatively connects 60 the last-named or release counting bar with mechanism carried by the carriage, so as to depress the bar automatically upon return of the carriage to the right, which makes unnecessary operation of the space-bar to count 65 the last word typed in a line. The first bar is thus a setting bar, and the other a release bar for the actuator, the bars being necessarily operated in proper sequence or both together, to effect a counting movement of 70 the actuator.

It is a feature of my invention to employ means operatively connected with the space-bar and certain other keyboard elements to control the actuator in such a way that the 75 latter cannot operate the register as long as the space-bar is held down, thereby safeguarding the register against being misoperated while holding the space-bar down, which has been possible heretofore. This is simply so and positively accomplished by having a branch on the latch-releasing rocking arm move up behind the actuator as the latch is released.

Another feature of the invention resides 85 in the construction for counting each typed numeral as a whole word by having the numeral-key-lever engage and depress both universal counting bars at the same time, and swing the actuator to initial register-operating position, and simultaneously move the actuator-latch to ineffective position, and also hold the actuator stationary against action of its return spring until the numeral-key is released, whereupon the actuator is 90 made effective for moving the units wheel of the register ahead one unit or figure.

Still another feature of the invention resides in means for safeguarding the register against control by movement of the platen- 100

carriage before the latter is returned all the way to the right for beginning a new line of typing by locking a connection between the carriage and the releasing universal counting bar against operation until the carriage is 5 fully returned to the right.

Other features and advantages will hereinafter appear.

In the accompanying drawings,

10 Figure 1 is a fragmentary cross-sectional view, front to rear, of an Underwood typewriting machine having the present invention attached thereto.

15 Figure 2 is a fragmentary perspective view of a typewriter-keyboard, showing mechanism of the present invention in normal starting position to be operated by keyboard elements of the typewriting machine.

20 Figure 3 is a fragmentary sectional view, front to rear, of mechanism of the invention disposed in normal position and enclosed in a case with a register for actuating the latter.

25 Figure 4 is a partial side view of the mechanism of Figure 3, shown in the position it takes after the first letter of an ordinary word is typed.

30 Figure 5 is a partial side view of the mechanism of Figure 4, in the position it takes when the space-bar is fully depressed immediately following the typing of a word.

35 Figure 6 is a fragmentary perspective view of mechanism arranged for operating the releasing universal counting bar by return of the carriage to the right.

40 Figure 7 is a partial top view of the mechanism shown in Figure 6.

A typewriting machine to which the present invention may be attached has a main frame 10 carrying a fulcrum rod 11 on which are pivoted key-levers, generally designated as 12, and which may include alphabet key-levers 13, numeral key-levers 14, a tabulator key-lever 15 and levers for other character-printing keys (not shown). A space-bar 16 is secured to a pair of levers 17, only one of which is shown, pivoted on a rock-shaft 18. Springs 19 and 20 return the space-bar and key-levers respectively to normal position after being depressed. A stop-piece 21 on the main frame 10 is disposed below the space-bar to limit the depression of the latter, and a stop-piece 22 on the space-bar engages under an off-set portion of the main frame to limit the return movement of the space-bar. The tabulator key-lever 15 may be connected by a link 23 to a laterally-pivoted column-tabulating mechanism, generally designated as 24, which carries a tabulator-stop 25. Upon depression of the tabulator key-lever 15, a spring-moved platen-carriage 26 is released from a letter-spacing escapement-mechanism (not shown) and the stop 25 is swung into the path of a counter-stop 27 on the platen-carriage 26 and arrests the movement of the latter to the left. Strik-

ing any one of the character-printing keys, generally designated as 31, will depress a key-lever 13 or a key-lever 14, and a bell-crank 28 connected to each lever swings a type-bar 29 against a platen 30, and actuates the above-mentioned letter-spacing mechanism through the usual interponents (not shown). Depression of the space-bar 16 also actuates the letter-spacing mechanism by means of an arm 32 on the shaft 18 and other known interponents (not shown). Hence, the parts described above may be the same as those in an Underwood typewriting machine.

Typewriter-word-counters of the class to which the present invention relates usually employ two depressible universal counting bars arranged to be swung downwardly by the depression of keys and other elements of the keyboard. Depression of one of these universal counting bars sets up or establishes an actuating condition in a register-operating mechanism, and depression of the other counting bar releases said register-operating mechanism and permits the latter to operate the register and also to be automatically reset in starting or normally ineffective position by spring action.

In the present device a universal counting bar 40 is supported on inverted L-shaped members 41, only one of which is shown in the drawings. The lower end of such a member 41 is pivotally fastened to the forward end of an arm 42 fixed on a laterally-disposed rock-shaft 43 whose left end may be journaled in a supporting member (not shown), which may be an integral projection upon or fastened in any suitable way to the left side of the main frame. The right end of the shaft 43 is journaled in a wall 44 of a housing or case 45, which may be fastened to the right side of the main frame 10 in any suitable way for enclosing a register 46 and certain register-operating mechanism to be presently described.

A second universal counting bar 50 is supported on two or more inverted L-shaped members 51, only one of which is shown in the drawings. The lower end of such a member 51 may be pivotally fastened to the forward end of an arm 52 fixed on a rock-shaft 53 laterally disposed in front of the shaft 43. The shaft 53 may be journaled in the same parts as the shaft 43. To permit the arms 42 to be rocked without striking the shaft 53, elongated holes 54 are provided in the arms 42 through which the shaft 53 passes.

To maintain the universal counting bars 40 and 50 in upright position, a lateral rod 55 (Figure 1) may be mounted in the main frame 10, and a link 56 loosely mounted on the rod 55 may extend therefrom rearwardly to be pivotally fastened to each of the members 51. In like manner, a flatly disposed

link 57 may loosely connect each of the members 41 with the rod 55, having an upturned ear 58 on its rear end, this structure permitting the counting bar 50 to be depressed without striking the links 57.

Usually, in word-counters of this class, various arrangements of series of teeth and notches, and the like, i. e., serrations, providing spaces, and shoulders or teeth upon the universal counting bars, have been proposed for counting words or word equivalents in different kinds of typed matter. It can be readily seen by those skilled in the art, as this application proceeds, that teeth and notches upon the universal counting bars of this device can be suitably positioned for counting typed words and word equivalents in different ways without departing from the scope of this invention. As illustrated in Figure 2, teeth 60 in the counting bar 40 may be positioned to be engaged by the key-levers 13, which are depressed when typing letters and also by the key-levers 14, whose depression types numerals and other characters, each of which it may be desired to count as a word, as when typing telegraph messages. In the edge of the counting bar 50, teeth 61 may be positioned to be engaged by the key-levers 14 and the tabulator-key 15. It will be noted that a deep notch 62 in the counting bar 50 is positioned to register with each superjacent key-lever 13 so that depression of the latter will not affect the counting bar 50. Certain teeth of the counting bar 50, as shown at 63, may have different heights to compensate for varying distances moved by the key-levers upon being depressed in typing. For a like reason, the teeth of the counting bar 40 may be arranged in varying heights, when desired. To provide for the shaft 53 to be rocked by depression of the space-bar 16, a short lateral pin 64 is fixed in the arm 52 so as to be disposed below the space-bar-lever 17.

Mechanism for operatively transmitting to the register 46 rocking motion of the shafts 43 and 53 caused by depression of the several elements 31 of the keyboard is mounted in the case 45. A drive pawl 70 operatively engages a ratchet-wheel 71, which may be fastened to the units wheel or disk of the register 46. The pawl 70 is pivoted on a pin 72 in the forward end of a lower member 73 of a substantially Z-shaped member 74, hereinafter called the actuator, which may be pivoted about a shoulder-screw 75 in the wall 44 and be spaced away from the latter by a collar 76. The pivot of the actuator 74 is preferably positioned adjacent the lower end of an upright portion 77 of the actuator. A spacing collar 78 is placed between the pawl 70 and the member 73 and around the pin 72, and a coil-spring 79 is wound around the collar 78 and has one end engaged behind the pawl 70 and the

other end engaged over the top of the member 73, so as to constantly urge the pawl 70 against the ratchet-wheel 71. A stop-pin 80, fastened in the lower end of the pawl 70 and positioned below the pivot thereof, projects through an over-sized hole 81 in the actuator-member 73, which serves as a stop to limit the movement of the pawl.

The forward actuator-member 73 and the pawl 70, supported thereon, are normally urged upwardly by a contractile spring 82, which has its upper end fastened to an upper rear projecting arm 83 of the actuator 74, and its lower end to a forwardly-extending arm 84 of a rocking member 85, fast on the shaft 43. The rocking member 85 has an upwardly-extending arm 86, to which is pivotally fastened the rear end of a stiff link 87, whose front end is pivotally connected to the actuator 74 above its pivot 75, in order to positively provide simultaneous rocking of both 74 and 85. The spring 82 urges the rocking member 85 and the actuator 74 counterclockwise, and a pin 88 is fastened in the end wall 44, to engage with and arrest the member 85, and the actuator connected to the latter is normally held inactive thereby in a position that will maintain the driving end of the pawl 70, carried by the actuator, against a tooth in the ratchet-wheel 71, as shown in Figures 2 and 3. In such position of the pawl, a figure (not shown), on each of the register-wheels of the register 46, will be disposed in front of a window 89 in the case 45.

When an alphabet-key and its key-lever 13 are depressed in typing the first letter of a word, the key-lever strikes against a tooth 60 of the counting bar 40 and swings the latter downwardly, thereby rocking clockwise the shaft 43 and the arm 86, fast thereto, far enough to move the actuator 74 clockwise until a locking lug 90 on the bottom of the actuator, and below the pivot thereof, is swung past a latch 91, pivoted on a screw 92 positioned forwardly from the lug 90 and held fast in the wall 44. A coil-spring 93 urges the latch 91 upwardly behind the lug 90, thereby preventing the return to starting position of the actuator 74 and also the counting bar 40, which is positively connected to the actuator by means of the mentioned link 87. This movement of the actuator swings the driving end of the pawl 70 downwardly below the tooth of the ratchet-wheel next below the starting position of the pawl, so that the actuator and pawl both occupy what may be termed a potentially operative position, as shown in Figure 4. A detent-pawl 94, of any suitable construction, may be employed to prevent backward rotation of the ratchet-wheel 71 during the described movement of the pawl. To permit the rocking member 85 to be rocked without interfering with the shaft 53, a portion of the member 85 is cut away at 95.

The counting bar 40 being latched in its depressed or operated position by the typing of the first letter of a word, typing of the remaining letters of an ordinary word has no effect on the counting bar 40 or the actuator 74. Upon operating space-bar 16, as is usual, after typing the last letter of a word, the lever 17, striking the pin 64 in the arm 52 rocks the shaft 53 clockwise. The right end of the shaft has fixed thereto a forwardly-extending rocking bar 96. A releasing pin 97, fast in the latch 91, is positioned to be moved up against the bottom edge of the bar 96 when the latch is swung upwardly into latching engagement with the actuator 74. This arrangement permits depression of the space-bar 16 to cause the bar 96 to press the latch 91 downwardly out of engagement with the actuator 74. By the same unlatching movement of the bar 96, an upwardly-extending integral arm 98 thereof having a laterally-disposed integral finger 99 is swung clockwise to bring the finger into engagement against the rear end of an upwardly and rearwardly extending stop-piece 100 held by a shoulder-screw 101 on the actuator 74, as shown in Figure 5. The actuator, therefore, is held stationary and is ineffective for operating the register 46 while the space-bar is depressed. Upon releasing the space-bar, the bar 96 is swung counterclockwise to normal position against a stop-pin 102 in the wall 44 by a spring 103 fastened to the bar 96 and to a pin 104 in the wall 44. At the same time, the spring 82 swings the actuator-member 73 and the pawl 70 up to normal starting position, and rotates the ratchet-wheel 71 one step ahead. It will be noted from inspection of Figure 5 that the actuator-shoulder or lug 90 moves far enough to the right between the instant of releasing the latch 91 and the engagement of the finger 99 against the stop-piece 100 to be free from interference with the latch as the latter is raised to normal position upon releasing the space-bar 16.

A numeral-key-lever 14, upon being depressed, engages against a tooth in each of the universal counting bars 40 and 50, which teeth may be arranged so as to cause the rocking of both shafts 43 and 53 to such an extent that the pawl 70 is swung downwardly to be disposed, as shown in Figure 5, one tooth-space below its starting position. Upon release of the numeral-key-lever, the ratchet-wheel will be advanced one step, thus counting a numeral or other desired typed character as a word. It is apparent that when a numeral key is operated, the stop piece 100 and finger 99 pass each other without functioning.

In doing fast work, a typist may inadvertently strike the space-bar 16 while the register is in its normal position. In such case, the finger 99 will be swung over and past the stop-piece 100 closely adjacent the outer

end of the latter. Then, should the typist strike an alphabet-key before the space-bar 16 and the finger 99 have been returned to normal position, the outer end of the stop-piece 100, upon swinging clockwise with the actuator 74, will strike against the lower surface of the finger 99. To guard against this possible engagement of the finger on the stop-piece stopping or retarding rapid operation of the alphabet-keys, the stop-piece 100 is pivotally mounted on the screw 101, and is yieldingly held in normal operative position against a pin 105 fast in the actuator 74 by a light coil-spring 106 around the screw 101, and may readily move out of the way of the finger when the latter is ahead.

It is desirable to automatically depress the counting bar 50 to count the last word typed in a line before returning the carriage, without operating the space-bar, which latter operation an operative might forget, from lack of habit of doing so, since it is not usually done in ordinary typing in which the words are not counted. To this end, an upwardly-extending link 110 has an elongated closed slot 111 in its lower end engaging about a pin 112 fast in a lug 113 on the counting bar 50. The upper end of the link 110 is pivotally fastened to an arm 114 adjustably secured by a set-screw 115 to a laterally-disposed splined rock-shaft 116, which also serves as a margin stop-rod for the typewriter, and which carries a margin gage-device 117 including a cam-faced tappet 118 mounted on a rearwardly-extending arm 119 splined on the shaft 116. The construction of the margin gage 117 may be substantially the same as that described in the patent to F. A. Hart, No. 1,237,641, except as otherwise noted herein-after.

According to this construction, a marginal stop-lock may engage the tooth 108 of the lock-bar 109 on the typewriter-frame in order to locate the stop 117 in a fixed position, which will determine the initial position for the carriage attained by the same in traveling toward the right.

A forwardly-extending L-shaped piece 120 is fixed on the front of the carriage 26 in such manner as to extend over the margin-stop-lock bar and carries a downwardly-depending cam-piece 121 arranged for engaging the tappet 118 and swinging the latter downwardly just before the carriage upon being returned toward the right is arrested in initial position by a usual margin stop 122, pivoted on the carriage, engaging with a usual counter-stop 123, thereby effecting the downward movement of the link 110 through the above-noted interponents. In order to prevent the link from being accidentally or intentionally actuated downwardly before the carriage has been fully returned to initial position at the limit of its rightward travel, a notch 124 is made in the rear side of the

tappet 118, and a latch 125 is pivoted about a screw 126 in the margin gage 117 to be normally pressed by a spring 127 into the notch, thereby controlling the counter by preventing the downward movement of the arm 119 and the link 110 until the latch is released. Just before the stops 122 and 123 are engaged, a forward end 128 of the L-shaped piece 120 engages an upturned lip 129 of the latch 125, and swings the latter out of latching engagement with the tappet, thereby permitting the arm 119, which carries the tappet, to be swung downwardly. The pin 112 is normally disposed in the upper end of the slot 111, which permits the counting bar 50 to be depressed by the space-bar 16 at any position of the carriage 26.

Since it can be readily seen that the register disclosed herein can be equipped with such devices as overthrow-preventing pawls, clearing-out keys, etc., of any suitable design, without affecting the scope of my invention, it is not considered necessary to show such devices in the drawings, especially as such devices are well known in the art.

Variations may be resorted to within the scope of the invention, and portions of the improvements may be used without others.

Having thus described my invention, I claim:

1. A word-counter for a typewriting machine having alphabet-keys and a space-bar, including a register, a spring-driven actuator therefor, means controlled by said keys for moving said actuator against its spring to an advanced position for operating said register upon its return movement, a latch for latching said actuator in its advanced position, means controlled by the depression of said space-bar for releasing said actuator from its latched condition, and a stop controlled by said space-bar for preventing the return of said actuator and the operation of said register until said space-bar is released.

2. In a word-counter for a typewriting machine having a keyboard, a register, spring-urged actuating mechanism therefor normally disposed in an ineffective position, means including keyboard elements for moving said mechanism to potentially effective register-operating position and locking it, means including other keyboard elements movable to a position effective for releasing said mechanism so that it may operate to actuate said register, and means to operate concurrently with said releasing means to hold said actuating mechanism from operating until after said keyboard means is released.

3. In a typewriting machine, a carriage, a margin-stop rod, a laterally-adjustable margin-stop on said rod, a word-counter, and means normally locked but effective to rotate said rod whereby to control said word-counter upon movement of said carriage when re-

turned to the right against said stop which first unlocks and next rotates said rod.

4. In a word-counter of the class described, a register, a spring-urged actuator therefor, means for moving said actuator to a potentially effective position whereby it is effective upon return movement by its spring to actuate said register, a latch for latching said actuator in said potentially effective position, and a displaceable member arranged to be moved to an operative position for disengaging said latch, said member having an arm for controlling the return movement of said actuator.

5. In a typewriting machine, a carriage, a rotatable margin-stop rod, a margin-stop adjustable lengthwise of said rod for arresting and determining the limit of the rightward travel of said carriage, a word-counter controlled by rotary movement of said rod, a latch for normally holding said stop-rod fixed against rotation, means effective to release said latch upon moving said carriage adjacent the limit of its rightward travel, and means rendered effective by movement of said carriage immediately after releasing said latch for rotating said rod in order to control said word-counter.

6. A word-counter for a typewriting machine having alphabet key-levers and a space-bar, including a register, a universal counting bar depressibly mounted under said alphabet key-levers, a universal counting bar arranged to be operated by pression of said space-bar, mechanism settable by said first-named counting bar into a potentially effective condition for operating said register, means for holding said mechanism in its set position, means controlled by operation of said second-named counting bar for releasing said mechanism in order to permit the same to operate said register, and instrumentalities operative with said second-named counting bar and mechanism to prevent the operation of said register while said space-bar is in depressed position.

7. A word-counter for a typewriting machine having a keyboard provided with a space-bar, including a register, normally ineffective operating mechanism for said register, keyboard-element-operated instrumentalities for rendering said mechanism effective to operate, and instrumentalities operative to said space-bar and operating mechanism for controlling the operation of said register and effective to prevent said operation of the same upon typing a word until said space-bar is both depressed and also released thereafter.

8. In a word-counter for a typewriting machine, a register, a pivoted spring-driven actuator therefor, means controlled by keyboard-elements of said machine, operative, upon typing the first letter of a word, to move said actuator to an initial operative position,

rendering the actuator effective to operate said register upon its return to normal ineffective position, a latch for latching said actuator in said initially effective position, a displaceably-mounted member operatively connected to a keyboard-element which is normally operated after typing said word, said member being effective upon operative movement to release said latch, and instrumentalities for controlling operative movement of said actuator upon release of said latch, said instrumentalities including a stop-piece projecting from said actuator and an arm on said member effective to be moved up against the end of said stop-piece when said actuator is in said effective position, said arm being positioned to pass by said stop-piece in such manner as to clear the latter when said actuator is in its normal ineffective position, whereby the operation of said last-named keyboard-element before the typing of a letter will be independent of said actuator.

9. In a typewriting machine, a carriage, a marginal stop-rod, a swingable marginal stop-member associated therewith, means normally latching said stop-member against rotary movement, means operated by movement of said carriage rightwardly to the limit of its travel corresponding to the location of said marginal stop-member for rotating said rod in one direction, a word-counter, a displaceably-mounted universal counting bar disposed under keyboard-elements of said machine for controlling the operation of said counter thereby, and a connection between said rod and said counting bar to permit said carriage to control said counter, said connection including a projecting arm fast on said rod, a link pivotally fastened to said arm and extending downwardly therefrom adjacent said bar, said link having a lengthwise closed slot in its lower end, and a pin fast in said counting bar and extending through the upper end of said slot, whereby rotary movement of said rod will depress said counting bar and control said counter, said slot-and-pin-arrangement permitting operative movement of said counting bar independently of said link, and preventing improper counter-controlling movement of said link independently of said carriage.

10. In a typewriting machine, a carriage, a rotatable marginal stop-rod, a word-counter, a universal counting bar displaceably mounted under keyboard-elements of said machine for controlling said counter, means normally locking said rod against rotation, said locking means being releasable to free said rod, means operated by lateral movement of said carriage for releasing and rotating said rod, and a positive connection extending from said rod to said counting bar uniformly effective to afford control of said counter by said carriage, whereby improper control of said counter by manipulation of

said connection by means outside of said carriage is safeguarded.

11. In a typewriting machine, a carriage, a marginal stop-rod normally held against movement, a word-counter, a universal counting bar displaceably mounted under keyboard-elements of said machine for controlling said counter, means for moving said rod upon predetermined lateral movement of said carriage, and a positive connection between said rod and said counting bar uniformly effective to afford control of said counter by said carriage in such manner as to bar improper control of said counter by manipulation of said connection by means outside of said carriage.

12. In a word-counter for a typewriting machine, a register having a ratchet-wheel, a pivoted actuator for said register positioned in the rear thereof, and having a pawl at its forward end disposed for operatively engaging said ratchet-wheel, a spring holding said actuator in normal position, a latching lug or shoulder on one edge of said actuator, spaced from the pivot thereof, certain keyboard-controlled means for swinging said actuator in one direction of rotation and moving the latter and said pawl to an effective position to advance said register one step or number upon return movement of said actuator by its spring, a latch pivoted in spaced relation from said actuator and disposed adjacent said shoulder for engaging the latter and holding said actuator in said effective position, a lateral pin fast in said latch, a pivoted member controlled by a keyboard-element for swinging said latch away from and out of engagement with, said actuator, stop-piece on said actuator spaced from the pivot thereof, and a projecting arm on said member having a lateral finger disposed for engaging said stop-piece immediately after said latch is moved to ineffective position, said spring being effective to swing said actuator far enough in a reverse direction of rotation during the interval between disengaging said latch and engaging said finger against said stop-piece to move said shoulder clear of said latch and leave said actuator free to be returned to normal under control of said arm which is operatively connected to said keyboard-element.

13. In a typewriting machine having a carriage, the combination with a word-counter, of a stop-rod movable in predetermined manner to operate said word-counter, a displaceable lock so related to said rod as to normally lock said rod against the predetermined movement, and means associated with said carriage for displacing and thereby releasing said lock upon return of said carriage to initial position to begin a new line, there being means to operate said word-counter through said movement of said rod upon release of said lock.

14. In a typewriting machine having type-keys and a space-key, the combination with a word-counter, of a reciprocatory driver therefor, means to enable the type-keys and the space-key to co-operate to advance said driver, and means to enable said space-key when held depressed to prevent the operation of said counter by any of the type-keys so long as the space-key is held depressed.

15. In a typewriting machine having type-keys and also having a space-key, the combination with a word-counter, of means rendering the space-key co-operative with said type-keys to operate said word-counter, and means effective while in the depressed position of said space-key to prevent operation of the word-counter by operation of said type-keys and also effective to permit operation of said word-counter during the upper stroke of said space-key to normal position.

16. In a typewriting machine having type-keys and also having a space-key, the combination with a word-counter, of means movable by said type-keys into potential operative relation to said word-counter, auxiliary means operable by actuation of said space-key for rendering said movable means effective to operate said word-counter, and additional means operating after said last-named means to prevent operation of the word-counter during the depression of the space-key.

17. In a word-counter for a typewriting machine, a register, a spring-driven actuator therefor, means for moving said actuator upon typing the first letter of a word to a potentially operative position, a latch for holding said actuator in said position, keyboard-elements for controlling said means, and additional means controlled by other keyboard-elements to act upon their movement in one direction, to release said latch and hold said actuator from operation of said register and to act upon their return movement to release said actuator to operate said register.

18. In a word-counter for a typewriting machine, a register, a pivoted spring-driven actuator therefor having a projecting member, keyboard-elements, means controlled by some keyboard-elements of said machine for moving said actuator to an initially-effective position, upon typing the first letter of a word, for operating said register upon return to its ineffective position, a latch for holding said actuator in said initially-effective position, a rocking member effective for releasing said latch upon being rocked in one direction by other keyboard-elements which are normally operated after typing the word, a projecting arm on said rocking member disposed in the rear of said projecting actuator-member, a laterally-extending finger on said arm, and a stop-piece yieldingly mounted on said actuator-member to be engaged by said

finger for controlling the return movement to ineffective position of said actuator.

19. In a word-counter for typewriting machines, a register, a spring-driven actuator for said register, means including keyboard elements effective upon typing the first letter of a word to advance said actuator to a potentially effective position for operating said register upon its return movement, a spring-pressed latch for holding said actuator in said potential operating position, means including another keyboard element normally operative after said word is typed and effective to release said latch, a stop piece on said actuator, an arm on said latch release mechanism cooperative with said stop piece so as to hold the actuator until after the release of said last mentioned keyboard element.

20. In a typewriting machine having type-keys and also having another key-board element operable normally after a typed word, the combination with a word counter, of means rendering said key-board element co-operative with said type-keys after being pressed and released to operate said word-counter, and additional means effective, while said key-board element is held in its depressed position, to prevent the operation of said word counter by said type-keys.

21. A typewriter word counter comprising an actuator and means for automatically setting the same for actuating the counter when an alphabet key is actuated, means including a reciprocable element of the typewriter for releasing said set actuator and means for stopping a second setting of said actuator until said reciprocable element has received its reciprocable movement.

22. In a typewriting machine, a carriage, a word-counter and type-keys, means movable by said keys into a potential operative relation to said word counter, means operated by said carriage near the end of a line movement to operate on said word counter and means effective to prevent operation of said word-counter by the movement of said carriage except near the end of said line movement.
